may be of any suitable known construction. A stack S of signatures 5 gathered in the order or sequence in which the same are to be sewn together in book form is supported on-edge by slightly inclined bars 2 and endless belts 3 and rests forwardly against a plate 4 (FIGS. 6 and 7). The folded backbone edges 6 of the signatures 5 in stack S, which edges will constitute the sewn spine of the book, should be down, and the closed ends or heads 7 of the signatures should be toward the left and hence, the leading edge in FIG. 1 of the illustrated embodiment. The bottom edge of the leading signature, at the right in stack S as viewed in FIG. 7, may engage adjustable stops 8, and as signatures are withdrawn one at a time from the forward end of the stack, the latter may be moved forwardly against stops 8 by intermittent operation of belts 3 in a manner well known in the art, such as by the cam-actuated linkage L shown in FIG. 10.

Novel means are provided for withdrawing the leading signature 5 from stack S and transferring the same to the continuously operating endless gripper conveyor C in suspended inverted position, i.e. with the backbone fold 6 uppermost, and the open edge portions of the signatures freely suspended from the conveyor grippers G. In the form shown, said means comprises a shaft 9 rotatably supported in plates 1, 1' and driven by power means M in a counterclockwise direction, as seen in FIGS. 5 and 7, through a gear train including gears 10, 11 and timing belt 12 (FIG. 5) which is driven from main power shaft D.

In a conventional manner, the lower edge 6 of each signature in stack S is engaged and drawn to the right below plate 4 (FIG. 7) by a plurality of vacuum suckers 13 of known construction mounted on stub shafts 14, 14' for pivotal reciprocation as indicated by arrows. Timed operation of the suckers and linkage L is effected by a disc cam 15 driven by shaft 9. The suckers are carried on hollow arms 16' mounted on and projecting radially from a hollow bar 16, the ends of which are carried by arms 17, 17' pivotally mounted on said stub shafts 14, 14'. A lever 18 integral with arm 17 carries a cam follower roller 18' which is held in engagement with cam 15 by suitable resilient means, such as a spring 15' connected to lever 18 (FIGS. 6 and 10). The cups or heads of suckers 13 are connected to a source of vacuum at appropriate intervals and in timed relation with the other functions of the apparatus through hollow arms 16', hollow bar 16, a flexible hose 20, a rotary disc valve 21 concentric with and driven by shaft 9, and a flexible hose (not shown) leading from the valve to a source of vacuum, such as a motor driven pump 19 (FIG. 1) all in a manner well known in the art.

The lower edge 6 of a signature 5 withdrawn by vacuum suckers 13 (FIG. 7) is then engaged by mechanical or suction-type gripper means carried by shaft 9 in a known manner. In the form shown, a plurality of mechanical grippers are mounted on a plurality of discs 22, 22 which may be identical and in effect constitute a drum. The discs 22 are in turn mounted on shaft 9 for rotation therewith and constructed to perform a dual function. Said gripper means comprises blocks 23 mounted on drum discs 22 near the periphery thereof and having arcuate gripping surfaces that form lateral extensions of the peripheral or rim surfaces of the discs for cooperation with gripper fingers 24 fixedly mounted on a shaft 25 that is eccentrically journaled in discs 22 and a disc 26 on shaft 9 for angular reciprocation relative thereto. A pinion 27 on one end of shaft 25 meshes with a gear segment 27' which forms one arm of a bellcrank pivotally mounted at 28 on disc 26 which rotates with shaft 9. The gear segment 27' carries a roller 29 which is held in engagement with a cam 29' by a compression spring 30 connected to the other arm of the bellcrank, said cam being secured to frame 1. Thus, at the proper time in the cycle of counterclockwise rotation of drum 22, 22, as viewed in FIGS. 7 to 9, gripper fingers 24 are moved into cooperative relation with blocks 23 to grip the lower edge 6 of a signature 5 which, as described above, has been segregated from the stack S by suckers 13 (FIG. 7). Upon continued rotation of drum 22, 22 the gripped signature is withdrawn downwardly

from the stack and carried in an arcuate path by the drum (FIG. 8).

In addition to carrying gripper means 23, 24 for removing and conveying signatures from stack S, the drum 22, 22 cooperates with a sector drum 31 to provide a friction or roll-type sheet or signature feeder to which signatures are delivered by said gripper means. In the form illustrated, sector drum 31 also consists of a plurality of discs which mate with the discs of the first drum 22, 22. As shown, the latter may also be a sector drum; that is, a drum having only a sectoral rim or peripheral surface of maximum diameter. Drum 31 comprises two identical sector discs mounted on a shaft 32 for rotation therewith. Said shaft is parallel to shaft 9 and is preferably driven by a gear 32' which is in constant mesh with drive gear 11 on shaft 9, whereby drums 22 and 31 are driven in opposite directions as indicated by arrows in FIG. 8.

Shaft 32 is journaled near its end in corresponding arms 33 of bellcranks 33, 33' which are pivoted on a transverse cross-bar 34 between the main frame plates 1, 1'. The bellcranks 33, 33' are resiliently urged in a counterclockwise direction as viewed in FIGS. 5 and 10 by compression springs 35 interposed between the arms 33' of the bellcranks and fixed brackets 35'. Said springs urge arms 33' against adjustable stops 36 which determine the minimum clearance between the sectoral rim surfaces *a* and *b* of drums 22 and 31, respectively. Suitable known means including a threaded member 36' may be provided for adjusting the compression of each spring 35 and thereby the pressure applied to a signature gripped between the sectoral surfaces *a* and *b* of the cooperating drum discs 22 and 31.

The sectoral rims *a* and *b* of sector drums 22 and 31 may but need not be of equal radius. The rotational velocities of the two drums are, however, so chosen that the sectoral surfaces 35 thereof are face-to-face when passing through the plane containing the drum axes (FIG. 9) at the same time to bite or grip a signature 5 therebetween under the pressure of springs 35 and to thus frictionally feed the signature upwardly. The relative speeds of rotation of the two drums 22 and 31, as determined by the diameters of drive gears 11 and 32, are such that the linear speed of the sectoral rim surfaces *a* and *b* which engage opposite sides of the signatures are substantially equal.

Thus, when the leading edge 6 of a signature 5 engaged by gripper means 23, 24 has been moved from the position illustrated in FIG. 8 to the plane containing the parallel axes of shafts 9 and 32, the adjacent sectoral surfaces *a* and *b* will cooperate to bite and frictionally grip the edge 6 of the signature while at about the same time, cam 29' will operate to actuate gripper fingers 24 to open position (FIG. 9) and thus release said edge of the signature. Following such release the signature is fed upwardly by drums 22 and 31 and is preferably guided by a plurality of stationary depending bars 37 in inverted position from that which it occupied in the hopper H. The now upper edge 6 of the signature, which may be the backbone fold thereof, is directed into one of a plurality of gripper mechanisms G of the endless conveyor C to be next described. Each gripper G, as it passes above drums 22 and 31, is moving continuously and horizontally toward the left (FIG. 1) in a line parallel to the axes of said drums and perpendicular to the direction in which the signature is being fed by said drums. The timing of the cooperating mechanisms is such that an open gripper G receives the edge of the signature and closes to support and convey the same in suspended position (FIG. 7) at the same time that the signature is released from the grip of drums 22 and 31; that is, when the trailing end of at least one of the sectoral rim surfaces *a* and *b* moves above the plane containing the axes of said drums, thereby freeing the signature for movement in a line parallel to said axes toward the signature-opening section O. The discs making up drum 31, 31 are preferably angularly adjustable on shaft 32 for varying and hence, timing the release of signatures from the bite of drums or rolls 22 and 31.

It will be understood that the stops 36 are so adjusted that the minimum distance between sectoral surfaces *a* and *b*,

when they are face-to-face between shafts 9 and 32, is somewhat less than the thickness of the thinnest sheet or signature to be handled. Thus, each signature fed into the bite of the drums 22 and 31 will force drum 31 away from drum 22 against the pressure exerted by springs 35 to thereby provide the necessary biting or gripping action for feeding the signatures upward. If desired, the timed release of a signature from the bite of drums 22 and 31 may be effected by suitable cam or eccentric means (not shown) for periodically further pivoting bellcranks 33, 33' and hence, drum 31 clockwise about rod 34 and away from drum 22 against the pressure of springs 35. Although it is preferable that drum 31 be positively driven as illustrated, the same may be an idler drum, if desired, since drum 22 is positively driven. In the illustrated embodiment, the diameter of drum 31 is only half that of drum 22. Hence, drum 31 is driven at twice the angular speed of drum 22 and accordingly, makes a lost revolution while gripper means 23, 24 returns to position for withdrawing another signature from the hopper.

SIGNATURE GRIPPER CONVEYOR

(FIGS. 1, 5, 7 and 11-15)

The gripper conveyor C is of novel construction and in the form shown comprises a single endless belt or chain 38 supported primarily by a driving sprocket 39 and an idler sprocket 40 mounted on horizontal shafts 39' and 40', respectively, journaled in parallel beams or rails 41 and 41'. Conveyor chain 38 is continuously driven in a clockwise direction as viewed in FIGS. 1 and 13 in timed relation with hopper feeder F and other mechanism making up the complete apparatus. As shown, sprocket 39 and hence, chain 38 are driven from main shaft D through a transverse shaft on which pulley 42 is mounted (FIGS. 22 and 23), a timing belt 42', gears 43 and 43', overload clutch 44' and shaft 39'.

Chain 38 carries a plurality of equally spaced novelly constructed signature-gripping devices G including signature clamps capable of pivoting or rotating relative to the chain. In the form illustrated each gripper mechanism, the details of which are shown in FIG. 11, is rotatably supported by a swivel plate 44 secured by stud bolts 45 to ears extending laterally from special links 46 of the chain. Plate 44 is spaced from said ears by a thin flat plate 47, the edges of which ride in grooves in elongated bars 48 secured to the inner adjacent faces of beams 41, 41' (FIG. 14) near the upper and lower edges thereof. The guide plates 47 and bars 48 thus serve to provide support for the upper and lower reaches of chain 38 to prevent sagging thereof. A pivot pin 49 is journaled in an opening in swivel plate 44 and has a flange or enlarged head which rests on the swivel plate within a hole through guide plate 47. Mounted on the reduced projecting end of pin 49 for rotation therewith is a generally square Geneva gear plate 50 having bevelled corners and radial corner slots and a bifurcated body member 51 secured to the pin by any suitable means such as a transverse dowel. Plate 50 and member 51 are linked together by tube 52 which provides a recess for a compression spring 53 and a plunger 54 urged outwardly by the spring.

The outer end of spring-pressed plunger 54 engages a clamp bar 55 pivotally mounted between the furcations 51' of member 51 and is effective to normally hold said bar in the dotted line position shown in FIG. 11. A generally channel-shaped gripper jaw 56 is suitably secured, such as by welding, across the outer ends of the body member furcations 51'. When a gripper mechanism G is suspended from the lower reach of chain 38, the jaw 56 forms in effect an inverted V with an inclined skirt c to guide and receive the upper edge 6 of a signature 5 that is fed upwardly by drums 22 and 31 in the manner above described. The inclined side d of jaw 56 has a plurality of slots e to receive the angle-shaped fingers 57 of a cooperating clamping jaw 58 mounted on one end of bar 55. A cam follower roller r is mounted on the other end of bar 55 for engagement with a cam bar 60 adjustably mounted on the lower edge of beam 41' (FIGS. 5a and 13a).

When a clamping or gripping device G approaches the bottom of sprocket 40, the guide plate 47 thereof enters the grooves in lower bars 48 and roller r engages the inclined surface f of cam bar 60 to thereby pivot bar 55 and clamp jaw 58 to the full line position in FIG. 11 with the jaws 56 and 58 separated for receiving the edge 6 of an upwardly fed signature 5. When the roller r rides off the more sharply inclined surface g of the cam bar 60, the clamping jaws are rapidly moved to dotted line position (FIG. 11) and hence, closed on the signature by spring plunger 54. At the same time the signature is released, as above described, by rolls or drums 22, 31 to permit movement of the signature toward the left (FIG. 1) by gripper conveyor C while suspended from the gripper device G.

While the suspended signature is being thus continuously horizontally advanced, the same is opened to its center in a manner to be hereinafter fully described, and before the opened signature is deposited onto a saddle it may be desirable to turn the same through a half or quarter revolution. Novel means provided for this purpose comprise the Geneva gear plate 50 the edge portions of which preferably overlap the outer edges of grooved guide bars 48. At the location where it is desired to effect the turning of the gripper jaws and hence, the signature clamped thereby, there is provided one or more indexing posts 59, two being shown, for effecting a half revolution turn (FIGS. 12 to 14). As shown, these posts are mounted on a right-angle bracket 59' secured to beam 41 and extend into the path of one edge of Geneva gear plate 50 for cooperation with the radial slots in the corners thereof in a conventional manner, so that a quarter turn of the clamp 56, 58 is effected by each post, the latter functioning as stops about which the gear plate pivots in response to linear movement thereof by the conveyor chain 38. Various positions of the gear plate 50 as it approaches and passes indexing posts 59, 59' are illustrated diagrammatically in FIGS. 15a, 15b and 15c. A second bracket 59' with two indexing posts 59 is mounted in inverted position on the upper edge of beam 41 (FIG. 14) to index each gripper during the return leg of each conveyor cycle and to thereby restore it to proper orientation for picking up another signature from the drums 22 and 31 of the hopper feeder F.

As each gripper device G approaches the left-hand end (FIG. 1) of the lower reach of chain 38, the cam follower roller r engages a second cam bar 60' which is similar to cam bar 60 and is mounted on the lower edge of beam 41 (FIGS. 12 and 13) to the left of turning station T and above saddle conveyor B (FIG. 1). The gripper jaws 56, 58 are thus opened to release the opened and rotated signature, permitting it to fall astraddle of the inverted V-shaped saddle of conveyor B to be hereinafter described. Arcuate guides 61 (FIGS. 12 and 13) may be provided at the upper edges of beams 41 and 41' for engagement by Geneva gear plates 50 to direct gripper guide plates 47 into the grooves in the upper guide bars 48 above sprocket 39.

SIGNATURE-OPENING SECTION

(FIGS. 1, 16 and 17)

The invention contemplates novel apparatus operable in combination with gripper conveyor C to open a signature suspended from gripper jaws 56, 58 while the same is continuously advanced toward the left by the conveyor. In the form shown said apparatus comprises a supporting rail or beam 62 mounted on vertical toothed racks 62' directly below and parallel with conveyor chain 38. Beam 62 and equipment mounted thereon may thus be vertically adjustable by means of a handwheel 63 through a suitable gear train (not shown) including gears on shaft 64 in mesh with the racks 62' (FIG. 1). Although a plurality of signature-opening units, both suction and mechanical, are illustrated at both sides of the path of the moving signature, it will be understood that in the broadest aspect of the invention, only a single-opening unit on either side is required.

Two suction- or sucker-type signature-opening units 65 are shown mounted on each side of rail or beam 62 on brackets 66 secured to the beam, said units being spaced and alternately positioned lengthwise of the beam. For purposes of description, the four illustrated units 65 are identified as first, second, third and fourth in accordance with the order in which a signature is conveyed past the same by conveyor C. Each unit includes a rotary-type disc valve having a fixed disc 67 and a cooperating rotary disc 68 drivably connected to a shaft 69 journaled in a bracket 66, the axis of the shaft being at an angle to the vertical and diverging downwardly from the plane of the signature 5 suspended from gripper G.

A suction-type separating device 70, which is preferably of the type disclosed in Perry et al. U.S. Pat. No. 2,799,499, is mounted on valve disc 68 for rotation therewith. Said disc and the housing of the separator device may be integral as shown. Valve disc 67 is connected through suitable tubing to a source of vacuum and adjacent faces of two discs 67 and 68, perpendicular to shaft 69, are cooperatively ported and channelled and thus connected to the interior of the cylinder of device 70 so as to alternately subject the latter to vacuum and atmospheric pressure for predetermined intervals during each revolution of the valve disc 68 and device 70. Each device 70 embodies a flexible rubber suction cup 71 mounted on a reciprocable piston 72 and, in a manner fully disclosed in the above-mentioned patent, the piston and cup 71 are projected outwardly by differential internal pressures when the device is subjected to vacuum through valve 67, 68 until the cup engages and is sealed by a signature or the like across its face or mouth. When cup 71 is thus sealed by a sheet of a signature, the effect of vacuum on the piston is automatically reversed, and the piston and cup are returned to normal retracted position by spring pressure and vacuum while the sheet is held against the cup by the differential pressure acting thereon. The paper or sheet sealing the mouth of the cup is released when the interior of the device is, upon further rotation thereof, disconnected from the vacuum source and connected to atmosphere through the porting of valve 67, 68.

The sheet separator device 70 is so mounted on the inclined or tilted valve disc 68 that the axis of piston 72 thereof will be substantially horizontal when it is perpendicular to a passing signature 5 with the cup 71 facing the latter as shown at the right in FIG. 17 and at the lower left in FIG. 16. Valve disc 68 and hence, suction device 70 are continuously rotatably driven so that suction cup 71 moves in the same direction and at approximately the same speed as the suspended signature when the two are adjacent. It is at this time that the device 70 is connected to the vacuum source through rotary valve 67, 68 and the cup 71 is projected against the side of the signature near the leading lower corner thereof to effectively grip the outermost sheet or folio and separate it from the remainder of the signature. Upon continued rotation of gripping device 70 and simultaneous advance of the signature by conveyor C, the vacuum-gripped sheet or folio is withdrawn outwardly from the signature and upwardly at an angle determined by the tilt of valve disc 67.

To improve the effectiveness of the sheet-separating devices a signature guiding and backup plate 73 is provided opposite each unit 70 adjacent the path of the signatures. Each said plate is preferably bent at its right-hand end (FIG. 16) away from the path of the signature to guide the latter between the plate and the adjacent separator unit 70. Plates 73 are mounted on straps 73' secured to beam 62. These straps may be somewhat flexible to permit some yielding of the backup plates while permitting firm engagement of the suction cup with the signature. A stop 74 may be adjustably mounted on the housing of device 70 for limiting the outward movement of cup 71 toward the signatures.

When the leading lower corner of the outermost sheet or folio of a signature has been gripped by a suction device 70 and suddenly pulled away by the retracting suction cup as explained above, there is danger that one or more adjacent sheets of folds (folios) may follow in the absence of sufficient

air pressure therebetween. This undesired result is prevented by an arcuate bar 75 which is mounted on device 70 and trails cup 71 in tangential relation to the suspended signature. Thus, the sheet or fold which is gripped by the suction cup and is being separated from the remainder of the signature will be bent rather sharply at the point of tangency and contact between bar 75 and the side of the signature. The inherent force of attraction which would otherwise cause an adjacent free sheet to follow the gripped sheet is overcome by the resistance of the free sheet to bending sharply. After initial separation at the bottom of the leading edge 7 of the signature, the air between the separated portions assists in the further and complete separation as desired.

The rotatable elements 68, 70 of the several units 65 are continuously driven in timed relation with each other and with the other mechanisms of the apparatus. In the form shown the fourth signature-opening unit 65 is driven from main drive shaft D (FIGS. 16 and 17) through a right-angle drive in gearbox 76, transverse shaft 77, a right-angle drive 78, splined vertically adjustable shaft 79 and a flexible angle coupling 80 to shaft 69. The third unit 65 is driven from vertical shaft 79, right-angle drives at opposite ends of a horizontal shaft 81 journaled in brackets 81' secured to beam 62, a vertical stub shaft 82' and a flexible coupling 80. The shafts 69 of the first and second separator units 65 are drivably connected to the shafts 69 of the second and fourth units 65, respectively, by timing belts 82. The rotation of each suction unit 70 is so timed that its cup 71 will be adjacent to and facing the path of each signature as the leading marginal edge or head 7 of the signature passes the same location. It will be seen that the first and third units 65 are rotated clockwise as viewed in FIG. 16, and the second and fourth units are driven counterclockwise.

Means are provided for completing the sheet separation initiated by a suction unit 70 and for supporting and maintaining a separated sheet or fold in open position with respect to the remainder of the signature during continued movement thereof by gripper conveyor C after the same is released by the suction cup 71. In the illustrated embodiment said means comprises a guide bar 83 in combination with each suction gripper unit. The right-hand end of each said bar as viewed in FIG. 16 is positioned between the path of the suspended signatures 5 and the path of the suction cup of the adjacent suction unit 70. Thus, as a signature is moved toward the left by conveyor C, the bar 83 enters the space between a sheet or fold that has been gripped and separated by the suction cup and the remainder of the signature. Each guide bar 83 is supported by suitable brackets 83' secured to beam 62 and extends upwardly and outwardly from the signature path in the direction of signature advance. Thus, after initial separation of the leading edge portion of the outermost sheet or fold at one side of a signature by a rotating-suction device 70, the separated sheet is released by the latter to fall against a rod 83 and is thereby further separated and lifted to ride over other mechanism, such as the other suction head assembly 70, on the same side of the signature path.

The composition of some signatures is such that two sheets or folds must be individually separated in order to open the signature to its center. This is true in the case of an inserted signature of the type shown in FIG. 3. In this event, the outermost fold is separated by the first suction unit encountered on one side of the signature path the inner fold or sheet is separated in the same manner by the next unit on the same side of the signature path while the first separated sheet is guided and supported by a guide bar 83. If desired, more than two signature-opening units may be provided on each side of the signature path. When any one or more of these units is not required for opening a signature passing through the apparatus, the unused units may be disconnected from the source of suction at a remote valve under control of novel programmer means P to be hereinafter described.

If desired, the suction units 70 on both sides of a signature may be rendered operative to open a signature from both sides, but this is not normally necessary or desirable. Nor-

mally, a signature is opened to its center by separating the sheets or folds at only one side of the center thereof. The other side or half of the signature remains vertically suspended until it approaches the signature-turning station T and is there engaged by means adapted to deflect it sufficiently to permit the opened signature to advance astraddle a turnaround shield or saddle 84. Said means are shown as comprising a rudder-type deflector plate or paddle 85 mounted on a vertical pivot 85' on beam 62 in the path of the suspended signatures. Paddle 85 may be pivoted between the full and dotted line positions thereof shown in FIG. 16 in any suitable manner, such as by a spring to move it to one position and a solenoid 86 having its plunger pivotally linked thereto for moving it to the other position. The position of guide 85 is selected to direct the suspended or unopened side of a signature to the appropriate side of the plough-shaped nose of turning saddle 84.

In the event the signatures are of the so-called lap type having the sheets or folds of one-half thereof longer and hence, extending beyond the sheets of the other half at the front edge of the signature, i.e., the lower edge as viewed in FIGS. 2 to 4, it may be desirable to open the same mechanically without the application of suction thereto. Novel means are contemplated by the invention for this purpose, and in the form shown, comprise a lap opening blade 87 and a suitable actuator 87' therefor, both mounted on a bracket 88 secured to beam 62. The blade 87 is pivotally mounted at one end on a surface of bracket 88 which is preferably upwardly and inwardly inclined toward beam 62. The blade is also pivotally connected intermediate its ends to a reciprocable plunger of actuator 87', the axis of which is similarly inclined upwardly and away from the viewer in FIG. 16. The plunger may be actuated by fluid pressure, resilient means, electromagnetic means or a combination thereof in any suitable known manner. For example, the blade 87 may be moved to its operative (dotted line, FIG. 16) position by connecting the actuator to a source of vacuum and may be retracted to full line position by resilient means when the vacuum connection is broken.

When lapped signatures are processed, the beam 62 and the equipment mounted thereon is elevated to a position such that the lapped edge of a signature suspended from a gripper G extends below the lower edge of a backup plate 73 positioned between the lap-opening unit 87, 87' and the signature, the lapped side of the signature being remote from the plate. Thus, when blade 87 is actuated to dotted line position slightly below plate 73 the edge of the free end of the blade in line with guide rod 83 will engage the lapped edge of an advancing suspended signature and steer or direct it onto said guide rod, whereby the signature will be opened to its center as it advances toward the left (FIG. 1). To avoid the likelihood of sheets from the short half of the signature following the lapped half as the latter is deflected by blade 87, the curved bar 75 on the suction assembly 70 opposite the lap opener assembly may be rotated 180° from the position illustrated in FIG. 17 so that the arcuate portion thereof will extend across the face of the suction cup 71. When thus positioned, the arcuate bar will tangentially engage the signature above the opening blade 87 and the bottom edge of backup plate 73. The lapped portion of the signature being moved to open position by blade 87 will then be caused to bend rather sharply at the bar 75, thereby preventing the sheets of the unlapped portion from following. A second lap opening assembly 89, 89' may be positioned on the other side of beam 62 for use when the lapped half of the signature is on the near side as viewed in FIG. 16. Inasmuch as the first and second units 65 will not be used when lap openers 87 and 89 are to be used, the vacuum connections thereto may be made interchangeable.

SIGNATURE TURNAROUND

(FIGS. 1, 16, 18 and 19)

In a manner and by means fully explained above, the swivel grippers G are rotated 180° with the signature suspended

therefrom as the gripper passes the Geneva gear-indexing pins 59 on bracket 59' at the lower edge of rail 41 above shield or saddle 84 (FIG. 1). Novel means are provided on beam 62 at this location for maintaining the signature in opened condition while it is being turned end-for-end. Said means consists of the saddle or shield 84 mounted for vertical adjustment on and with beam 62. As shown the saddle comprises a vertical side plate 90, a portion of the upper edge 91 of which tapers downwardly to the right (FIG. 1) to the vicinity of rudder 85, and the lower left corner portion 91' of which is bent outwardly to guide the suspended one-half of the opened signature onto the plough-shaped nose 92 of saddle conveyor B. A horizontal top plate 93 extends rearwardly (FIG. 1) and an inclined plate 93' joins the tapered edge 91 of side plate 90 with the right-hand edge of horizontal plate 93 to thereby form a wedgelike nose that enters the center of the traveling opened signatures carried by grippers G. As a gripper carrying an opened signature passes the indexing pins 59 on bracket 59' above saddle 84, the gripper and signature are turned a half revolution counterclockwise as viewed from the top in FIG. 1 while the separated halves of the signature are held apart by the saddle 84.

As a turned signature moves off of and beyond saddle 84 still supported by a gripper G, the near side thereof (FIG. 1) is guided by surface 90, 91' and saddle nose 92 into engagement with the near side of the inverted V-shaped conveyor saddle 94. The other half of the opened signature drops off of surface 93 into engagement with the opposite or far side of the nose 92 and conveyor saddle 94. When the full length of the turned signature has advanced to a position above saddle 94, the roller r of the gripper engages and passes across cam block 60' whereupon the gripper jaws 56, 58 are opened, and the signature is released to drop astride saddle 94 properly oriented for feeding into a book-sewing machine.

PUSHER SADDLE CONVEYOR AND SIGNATURE-CONDITIONING MECHANISM (FIGS. 1 AND 19 TO 25)

40 In the form shown saddle conveyor B is of the pusher type comprising an endless belt or chain 95 (FIG. 19) mounted on horizontal sprockets 96 and 96' which are in turn rotatably supported by a suitable frame structure 97. Sprocket 96 and hence, chain 95 are driven in timed relation with conveyor chain 38 by a vertical shaft 98, a right-angle drive 98' (FIGS. 1 and 26), horizontal shaft 90 and a sprocket 99' (FIGS. 12 and 13) driven by chain 25.

45 The inverted V-shaped saddle 94 of the conveyor B comprises a member 100 that forms one side thereof and has an upper marginal edge portion 101 which is bent down to form the upper edge or apex of the saddle and an inclined flange which is the upper portion of the other side of the saddle. The remainder of said other side consists of a plate 102, the upper edge of which is spaced from the lower edge of flange 101 to provide a longitudinal slot 103 on the same horizontal level with chain 95. At the receiving end of saddle 94, the sloping sides 100 and 102 thereof are joined by the wedge-shaped nose 92 which underlaps the turnaround saddle or shield 84. A plurality of flight fingers or pushers 104 are equally spaced on chain 95 and extend into slot 103 to engage and push the signatures along the saddle in desired spaced relation. Fingers 104 are mounted on links of chain 95 and may be guided between elements of frame assembly 97 by pins 105 that ride in a groove 106 (FIG. 20).

50 Novel means are provided by the present invention for treating or conditioning the center or backbone fold 6 of a signature while the same is being advanced on saddle 94 to thereby insure a snug fit by the signature on the saddle of a book sewer and hence, a better quality book. In the form shown, said means comprises two pairs of cooperating rollers 107 and 108. Rollers 108 are dislike with bevelled or blunt V-shaped peripheral edges and are mounted for free rotation on the saddle-supporting frame 109 which also supports the sides 101, 102 of the saddle 94.

The uppermost edges of rollers 108 project through a slot 110 in the apex or crown of saddle 94 to the same level as or slightly higher than said crown for cooperation with rollers 107 which have V-groove peripheries (FIGS. 22 and 24). Rollers 108 may have some clearance for axial movement on their supporting shafts to insure proper registry with the V-shaped peripheries of rollers 107.

Rollers 107 are mounted between spaced blocks 111 on shafts 112 rotatably supported by said blocks. Shafts 112 project to the right (FIG. 22) and each has a polyvee pulley 123 mounted thereon. The assembly thus comprising blocks 111 and rollers 107 is floatingly mounted on laterally spaced bars 113 which depend from beams 114 that form extensions of beams 41, 41'. The mounting of roller assembly 107, 111 is effected by two vertically spaced transverse tie bars 115 and 116 that connect and space blocks 111 and slidably extend through centrally disposed slots 117 in depending bars 113. The lower tie bar 115 is preferably cylindrical in slots 117 and has a relatively close sliding fit in the slots. The upper tie bar 116 is preferably rectangular in cross section in slots 117 with a loose fit therein. The roller assembly 107, 111 is thus free to move vertically within the limits of slots 117 and to rock through a small angle about bar 115 as a pivot which is in a common plane with and midway between roller shafts 112.

The above-described roller assembly is suspended by a pair of tension coil springs 118, 118 adjustably interposed between tie bar 116 and a fixed transverse bar 119 (FIG. 22). Also adjustably interposed between bars 116 and 119 is a compression spring 120. The tension of springs 118 and the compression of spring 120 are normally adjusted so that the bottom of the peripheral V-grooves in rollers 107 will be spaced a short distance above the bevelled peripheries of disc rollers 108. The adjustment of the springs and the distance between cooperating rollers in the absence of a signature are determined by the thickness range of the center or backbone folds of the signatures to be handled at any time. Said distance should be somewhat less than the thickness of said fold of the thinnest signature, but the differential spring pressure asserted against the fold of the thickest signatures passing between the rollers should not be great enough to damage the signatures. This adjustment is not difficult to achieve with the illustrated screw-threaded adjustment means as seen in FIG. 22.

Rollers 107 are preferably driven by a polyvee belt 121 and a pulley 122 mounted on an extension of shaft 39' which drives sprocket 39. The belt is held taut and in engagement with the tops of circumferentially ribbed pulleys 123 by a vertically adjustable idler or takeup pulley 124. The drive ratio is such that the signatures passing between rollers 107 and 108 on saddle 94 will be advanced by the rollers as fast as and preferably slightly faster than the same are advanced by pushers 104. This may be desirable to prevent crowding of and possible damage to the signatures by pushers 104 while the same are gripped or pressed between rollers 107, 108.

It will be apparent that as a signature traverses saddle 94 between the pairs of rollers 107, 108 the yieldable pressure applied thereby will effectively press any sharp fold out of the backbone 6 of the signature. The folds of the several sheets will be virtually unitized in a compact backbone fold that will fit snugly on the sewing saddle of a book-sewing machine, for example. After a signature is thus conditioned, the same may be forwarded by a pusher 104 onto the infeed saddle conveyor of a sewer (not shown) which further advances it in a manner known to the art onto the sewing saddle of the sewer.

MAIN DRIVE

(FIGS. 1 and 22)

The main drive shaft D from which power is taken for driving the several mechanisms described above is driven by an electric motor M. As shown, (FIGS. motor is drivably connected to main shaft D by a variable speed pulley 125, belt 126, pulley 127, countershaft 128, pulleys 129 and 130, and

5 timing belt 131. The latter also drives a pulley 132 which may be connected to drive a sewing machine (not shown) through a coupling 133 (FIG. 1) in timed relation with the signature feeder described above. This has the additional advantage of 10 making it possible and feasible to suitably program and control various mechanisms on the sewer, such as the paster and thread cutter, by programming means on the signature-feeding apparatus.

PROGRAMMER

(FIGS. 1 and 27 to 33)

To enhance the versatility of the above-described apparatus and to render the same quickly and easily convertible for handling different kinds of signatures and different mixtures of signatures of varying composition, novel timing or programming means are contemplated by the invention for selecting and controlling those mechanisms which are required to 15 function in each case. In the form illustrated, said programming means comprises a frame 134 mounted on beam 41 for rotatably supporting a driven sprocket 135 and an idler sprocket 136. A pedestal 137 supports an idler pulley 138 (FIGS. 1 and 31) for vertical adjustment and a chain support 20 and guide 139 between sprockets 135 and 136. A programming-chain assembly 140 of novel construction is 25 mounted on said sprockets and pulley to be driven counterclockwise as viewed in FIG. 1 by sprocket 135.

The chain assembly comprises a plurality of readily separable links, each of which includes an elongated bar 141 (FIG. 30) having at one side thereof a centrally disposed lug 142 with laterally extending pins 143 and at its opposite side a central notch 144 for receiving the lug 142 of an adjacent link and a pair of hooks 145 flanking the notch for engaging the pins 143 of the adjacent link. Lugs 142 and hooks 145 are 30 preferably of similar transverse section so that one complements the other to form inwardly projecting semicircular gear teeth which engage the sprockets 135 and 136 (FIG. 27). The outer surface of each bar 141 has a longitudinal groove 148 to receive one or more cam blocks 146 that may be secured in place by screws 147 or the like which have screw thread engagement with tapped holes or recesses in said blocks. In the embodiment shown each link bar 141 is drilled, by way of example, to receive up to nine cam blocks 146 in its groove 148. The horizontal reach 140' of chain 140 between sprockets 135 and 136 is supported and guided by chain guide 139.

Directly above chain guide 139 is a valve and switch frame or 40 box 149 is pivotally mounted on a bar 150 and is supported by 45 and detachably secured to frame bar 150'. A plurality of vacuum valves and electrical microswitches are mounted in box 149 for selective operation by cam blocks 146 when chain 140 is driven. As illustrated four vacuum line valves 154 are 50 combined in a unit 151 removably mounted in one end of box 149 on flanges 152 (FIGS. 29 and 32). The unit 151 may be 55 secured in box 149 and adjustably positioned in the direction of the line of movement of chain 140 by setscrews 153 which engage the bevelled surfaces of unit 151. Each of the four 60 valves 154 comprises a piston 155 slidable in a cylindrical passage 156 in the valve block and having a circumferential groove 157 intermediate the ends thereof. The threaded 65 reduced upper end of piston 155 slidably extends through a bracket 158, and the downward motion thereof is limited by a nut threaded thereon. The piston is normally held in its lower, closed position by a spring 159.

The lower end of each piston 155 carries a roller 160 which 70 is engageable by a cam block 146 moving beneath the same to lift the piston and thereby place two passages 161 and 162 in communication with each other through cylinder 156 and piston groove 157 which is normally axially displaced from at least one of said two passages. Each of the four passages 162 is 75 in constant communication with a source of vacuum through a common chamber 163 and a tube 164. Each of the passages 161 is connected by a tube 165 to the vacuum inlet of one of

the suction separator units 65 (FIG. 16). Each of the four valves 154 is in alignment with a different circumferential row of cam blocks 146 on chain 140, whereby each said separator assembly 65 may be selectively placed in communication with the source of vacuum in timed relation with a signature carried by conveyor C by selectively mounting cam blocks 146 on chain 140. When it is desired that any suction separator unit 65 shall remain inactive during each revolution thereof, no cam blocks are mounted on the chain in alignment with the appropriate valve 154. If it is desired to make use of the lap opening units 87 and 89, two of the valves 154 may be connected to actuators 87' and 89' in lieu of the connections to the first and second suction separators 65. Additional programmer valves and connections could, of course, be provided for the lap openers if desired.

For controlling other functional mechanisms of the apparatus, a plurality of microswitches 166 (FIGS. 1, 29 and 30) may be mounted in box 149 beside the vacuum valve unit 151 for selective timed actuation by cam blocks 146 on programmer belt 140. In the form shown, each switch 166 is mounted on a block 167 which spans flanges 152 and is adjustably positioned by setscrews 153 which engage the oppositely bevelled ends of the block. Actuating means for each of the switches comprises a plunger 168 (FIG. 27) slidably extending through block 167 and a bracket 169 secured to the latter. The plunger carries a roller 170 at its lower end and is normally held by a spring 171 in its lowermost position determined by a cross pin 172 with the roller preferably out of engagement with belt 140 but engageable by a cam block 146 in alignment therewith. A switch 166 may be normally open or normally closed depending upon its function and will be temporarily held closed or open, respectively, when its plunger is lifted by a programmer cam block 146. In the illustrated embodiment, four programming switches 166 are employed, one in circuit with solenoid 86 for controlling the position of guide rudder 85, one in circuit with the signature thickness detector or caliper 173 (FIG. 7), one for controlling operation of the paster in the sewing machine for the first and final signatures of each book, and another for controlling the operation of the sewing machine thread cutter after the final signature of each book is sewn into place.

Novel means are provided for driving programming belt 140 in timed relation and synchronism with the other mechanisms of the apparatus, said means being constructed to facilitate synchronization and to permit ready adjustment to compensate for signatures of different sizes and other variables. In the illustrated embodiment a sprocket 174 is mounted on a shaft 175 between beams 41 and 41' in mesh with conveyor chain 38 (FIGS. 12a and 29). A small pinion or gear 176 on shaft 175 meshes with a substantially larger gear 177 on a shaft 178 mounted in frame 134.

By reason of the facility with which links or bars 141 may be separated and connected, a programming chain or belt 140 may be readily assembled for the processing of book blocks containing different numbers and kinds of signatures in varying arrangements. The chain is assembled with one bar 141 for each signature and is driven at a speed such that it makes a complete cycle for each set of signatures making up a book block. If the number of signatures in each book block is insufficient to require a chain of sufficient length to encompass sprockets 135, 136 and idler pulley 138, it will be necessary to include two or more series of bars 141 in proper sequence in the chain and the latter will move a distance equal to each series for each book block.

As best seen in FIGS. 27 and 28, sprocket 135 is freely mounted on shaft 178 and is drivably connected thereto by means of a pair of arms 179 on the hub 180 thereof, setscrews 181 threaded through said arms, a cross bar 182 freely pivoted on shaft 178 within a diametrically extending slot 183 in said hub with one end clamped between setscrews 181, and a pin 184 which is carried by the other end of cross bar 182 and extends through an arcuate slot 185 between spokes in sprocket 135 for engagement with one of a plurality of circum-

ferentially spaced holes or recesses 190 in a disc or flange 186 secured in any suitable manner, as by welding, to shaft 178. Pin 184 is preferably provided with a hub 187 and is slidably mounted in a bushing 188 carried by cross bar 182. A compression spring 189 normally holds pin 184 in the driving position shown in FIG. 28.

It will thus be seen that sprocket 135 and hence, belt 140 may be angularly adjusted a limited amount relative to shaft 178 by complementary adjustments of screws 181, to effect minor timing adjustment of the programmer belt relative to the signature feeding mechanisms of the apparatus. A more extensive timing adjustment or variation may be accomplished by providing sprockets 135, 136 with teeth spaced more closely than the spacing of teeth 142, 145 on the chain. This permits an angular mounting adjustment of the chain equal to the distance between teeth on the sprockets. A similar adjustment may be effected without moving the chain relative to the sprockets by locating the centers of openings 190 on radii 20 passing centrally between adjacent teeth on sprocket 135. The sprockets and chain may then be shifted any angular distance which is a multiple of the angular distance between centers of said openings. Such adjustment may be accomplished by withdrawing pin 184 from one opening 190 in the flange 186 25 and rotating the cross bar 182 and hence, sprocket 135 relative to shaft 178 to a position at which the pin may be released to engage another opening in flange 186. This latter adjustment is useful to facilitate resynchronization of the feeder and programmer when such is necessitated for any reason, as when a book block sequence inadvertently contains too many or too few signatures.

DETECTOR MECHANISMS

(FIGS. 7, 19, 22 AND 24)

A book is often made up of signatures of at least two different thicknesses, such as 16-page and 32-page signatures. The present invention contemplates simplified means in novel combination with the programmer above described to detect at a predetermined location the absence of a proper signature, the presence of improper signature, or the presence of an improper number of signatures. Said detector means in the form shown comprises a contact roller 191 (FIG. 7) which is mounted on an insulating pivoted lever 193 positioned by tension spring 192 and stop 194 to engage the sectoral surface *a* of one of the drums 22 without engaging the remaining drum surface of lesser diameter. Thus, when a signature is not interposed between roller 191 and drum 22, an electrical circuit 35 may be closed at the contact between the roller and the drum to either signal the operator or stop the machine. To detect the presence of an excess number of signatures or one of excess thickness, two spring pressed contacts 195 and 196 are mounted for adjustment toward and away from mating contacts on insulating lever 193. Assuming that the books being collated and sewn comprise 16- and 32-page signature when more than one 16-page signature or a 32-page signature is present between roller 191 and the surface *a* of drum 22, the upper contact 195 is engaged to thereby close an electrical circuit to signal an operator or stop the machine if a 16-page signature is scheduled to be present at that location. The latter circuit includes one of the switches 166 of the programmer described above which is normally open but may be closed by 40 a suitably installed cam 146 on chain 140 during the interval when a single 16-page signature should be between drum 22 and roller 191. At other times, such as when a 32-page signature is scheduled to be present at the detector station, the circuit will be open at switch 166 so that the engagement at contact 195 will be ineffective. The contact 196 is adjusted to be closed and to thus close a signal circuit only if the signature or signatures present between roller 191 and surface *a* have a thickness appreciably in excess of the 32-page signature scheduled to be present. It is not necessary to include a programmer switch 166 in this latter signal circuit.

Novel detection means are also provided to detect a signature which may not have been properly opened before it is deposited on the saddle 94 of conveyor C. As shown, signal circuits are provided, including microswitches 197 (FIGS. 22 and 24) to be actuated to closed position when a signature or a part thereof is not properly astraddle the saddle 94 and therefore slides down one of the inclined side 100 or 102 against a switch actuating arm 198. Other absence or thickness detecting means of known construction may be located as desired along the path of the signature from stack S to the sewing machine, such as those illustrated at 199 (FIG. 19).

OPERATION SUMMARY

In summary the apparatus contemplated by the invention operates through suction means 13 and rotary grippers 23, 24 on continuously rotating drums 22 to withdraw signatures downwardly one at a time from a stack S of signatures stacked on edge in a predetermined repetitive sequence. After being carried approximately a half revolution by drums 22, each signature is released by grippers 23, 24 to be roll fed upwardly by cooperating sectoral surfaces *a* and *b* on drums 22 and 31 and into linearly travelling grippers G. Suspended from these grippers with backbone fold uppermost, the signatures are carried in predetermined spaced relation past the rotating suction-separating devices 65 and lap opening devices 87 and 89, one or more of which is readied by the programmer P for operation in the manner described above at the appropriate moment to open a passing signature to its center fold. The opened suspended signature is then turned if desired through 180° by swiveling the supporting gripper G through the action of Geneva gearing 50,59 in response to continued linear movement by conveyor chain 38. The moving signature which is maintained in open condition by shield 84 during the turning thereof is then carried astraddle of and released by grippers G onto the inverted V-shaped saddle 94 of pusher conveyor C. While traversing the saddle of the conveyor, the backbone fold of the signature is conditioned by the novel device R to fit snugly on a sewer saddle or the like to which it is next fed.

There is thus provided novel apparatus of simplified construction for automatically feeding signatures in a substantially continuously moving stream in accordance with a novel method from a stack of signatures in desired sequence to a book sewer or the like operated in timed relation with the feeding apparatus. Also provided in novel combination are novel apparatus for transferring signatures from a continuously operating rotary or planetary conveyor to a continuously operating endless linear conveyor, novel means for opening suspended signatures while the same are being linearly conveyed, novel means for turning suspended open signatures end-for-end while the same are being linearly conveyed and novel means for consolidating the folds of the individual sheets making up the center or backbone fold of a multiple page signature as the latter is moved along a saddle-type conveyor.

The embodiments of the invention in which I claim exclusive property or privilege are defined as follows:

1. In apparatus for handling sheetlike material, such as folded signatures, means for gripping a signature at a folded edge thereof and transporting the same in an arcuate path, a pair of continuously rotating drums for receiving and gripping said edge and roll feeding the signature upwardly in a generally vertical plane with said edge uppermost, continuously moving endless conveyor means, gripper means mounted on said conveyor means and movable horizontally thereby in said plane, means for opening said gripper means to receive said edge of the upwardly fed signature, means for closing said gripper means on said edge when the signature is released by said drums, means for opening a signature suspended from said moving gripper means, means for turning said gripper means with an opened signature relative to the conveyor means, means for holding the signature open while

the same is being turned with the gripper means, and inverted V-shaped saddle, means for opening said gripper means to release the opened signature to drop astraddle said saddle with said folded edge uppermost, means for pushing the signature along said saddle, and means for compressing the fold at said edge of the signature as the same is moved along said saddle, said last-named means comprising a rotatable disc extending through a slot in the apex of the saddle within the signature and a wheel with a V-shaped peripheral groove engaging the outer surface of said folded edge.

2. Apparatus for handling folded signatures comprising a first rotatable drum, a second rotatable drum adjacent to and cooperable with said first drum to grip and frictionally feed a signature edgewise in a plane, first gripper means revolvable with said first drum for conveying a signature edgewise in a path corresponding generally with the outer peripheral surface of said first drum and into the bite of said drums, means for opening the first gripper means to release the signature when the latter is gripped between said drums, endless conveyor means including second gripper means for receiving the leading edge of a signature fed by said drums and conveying the same edgewise in said plane in a direction normal to the direction in which the signature is fed by said drums, and means mounted adjacent the path of movement of the signature by said conveyor means for opening the advancing signature in response to the advancing movement of the signature.

3. Apparatus as defined in claim 2 wherein said means for opening the signature comprises suction gripper means for initiating the opening of the advancing signature.

4. Apparatus as defined in claim 2 wherein said means for opening the signature comprises stationary means for plowing the advancing signature open to its center.

5. Apparatus for handling folded signatures as defined in claim 2 wherein the advancing signature is gripped at its folded edge by and loosely suspended from said second gripper means.

6. Apparatus as defined in claim 5 for handling lapped signatures wherein said signature-opening means is stationary and extends across the path of the lap of the signatures.

7. Apparatus for handling folded signatures and the like comprising means for conveying a folded signature edgewise in suspended condition with its backbone folded edge uppermost, and suction-gripping means for opening the signature to its center by separating some of the suspended sheets of the signature from the remainder at the edge opposite said folded edge while the signature is advanced by said conveying means, said gripping means including a device rotatable about a fixed axis beside the path of the moving signature.

8. Apparatus as defined in claim 7 wherein said axis converges upwardly at an acute angle with the plane of the path of the signature suspended from the conveying means.

9. Apparatus as defined in claim 7 wherein said device comprises reciprocable gripper means for engaging and gripping the suspended signature sheet or folio adjacent said device.

10. Apparatus as defined in claim 9 wherein said gripper means are cyclically linearly reciprocable along an axis substantially normal to the plane of the broad surface of the signature.

11. Apparatus as defined in claim 9 wherein said gripper means reciprocate along an axis extending generally radially of and at an acute angle relative to said fixed axis.

12. Apparatus as defined in claim 9 wherein said device comprises rotary valve means for alternately connecting the reciprocable gripper means to a source of vacuum and to atmosphere during predetermined portions of each revolution of said device.

13. Apparatus as defined in claim 9 wherein said reciprocable gripper means is mounted to reciprocate in a line making an acute angle with said fixed axis.

14. Apparatus as defined in claim 9 wherein said reciprocable gripper means are fluid pressure actuated.

15. Apparatus as defined in claim 9 comprising means for continuously driving said conveying means and said device in

timed relation so that the signature-engaging surface of said gripper means is revolving in an arcuate path substantially tangent to the surface of the leading edge portion of the passing signature when it engages the latter.

16. Apparatus as defined in claim 9 wherein said device comprises an arcuate member tangentially engageable with the signature in the wake of the reciprocable gripper means.

17. Apparatus as defined in claim 9 comprising backup means in the line of the signature engaging reciprocating movement of said gripper means and positioned on the side of the path of the signature opposite the signature opening means.

18. Apparatus as defined in claim 1 wherein said signature opening means comprises a stationary guide bar extending longitudinally of the path of the signature and shaped to be engaged by said separated sheets when the same area released by said gripper means for further separating the sheets from the remainder of the signature in response to movement of the signature by the conveying means.

19. A method of handling folded signatures which comprises the steps of suspending a signature with the backbone fold thereof uppermost, conveying the suspended signature edgewise, gripping the lower leading edge portion of the outer sheet or folio of the suspended advancing signature with revolving reciprocable means to retard said sheet or folio and withdraw the same from the path of movement of the remainder of the signature, and plowing the withdrawn sheet or folio upwardly and away from said path in response to the advancing movement of the suspended signature to thereby open the latter.

20. A method as defined in claim 19 wherein the signature is suspended from a continuously moving gripper and further comprising the step of roll feeding the signature to the gripper in a direction at right angles to the direction of movement of the gripper.

21. A method of opening a lapped signature which comprises suspending the signature with its lapped edge lowermost, moving the suspended signature edgewise in a plane parallel to the broad surfaces of the signature and in a direction parallel to said lapped edge, and plowing the lapped half of the signature out of said plane in response to the movement of the signature to open the latter to its center.

22. The method of handling signatures which comprises the steps of gripping the backbone edge of a signature and withdrawing the same downwardly from a stack of signatures on edge, conveying the signature along a curved path to invert the same, releasing said edge and, without interrupting the advance thereof, simultaneously roll feeding the signature upwardly with said edge uppermost, simultaneously interrupting the roll feeding of the signature and gripping said edge by a continuously moving gripper to support the signature in suspension and continuously advance the suspended signature edgewise horizontally, opening and advancing suspended signature, and releasing the opened signature to drop a straddle a saddle.

23. The method as defined in claim 22 which includes the step of turning the advancing opened signature end-for-end before releasing the same onto the saddle.

24. The method defined in claim 22 wherein the step of opening the signature is to a substantial degree effected in response to the advancing movement of the signature.

25. The method as defined in claim 22 wherein the step of opening the signature is effected by plowing a lapped half of the signature away from the remaining half thereof in response to movement of the advancing signature.

26. Apparatus for opening folded signatures comprising means for conveying a signature edgewise in the plane of the broad surface thereof and suspended with the backbone folded edge thereof uppermost, means for separating depending sheets of said signature as the same is advanced by the conveying means including a suction gripper head revolvable about a fixed axis beside said plane, means for revolving said gripper head, means for connecting said gripper head to a

source of vacuum, means for projecting the revolving-gripper head generally radially from said axis into gripping engagement with a side surface of the signature adjacent the lower and leading edges thereof and for retracting said revolving-gripper head with the portion of the signature thus gripped by said head, means for disconnecting said gripper head from said source of vacuum to effect release of said gripped portion of the signature, and means for maintaining said portion of the signature separated from the remainder thereof as the signature is advanced by the conveying means.

5 27. Apparatus as defined in claim 26 wherein said gripper head is mounted to revolve in a plane inclined from the plane of movement of the signature whereby said revolving-gripper means lifts the lower edge of the gripped sheet of the signature while simultaneously withdrawing it from the remaining depending sheets.

15 28. Apparatus as defined in claim 26 wherein said gripper head is revolved at a speed approximately equal to the linear speed of the advancing signature.

20 29. Apparatus for opening folded signatures comprising a stationary frame, a supporting beam mounted on said frame, means mounted on the frame for conveying a suspended signature edgewise in a path above and along said beam, and 25 means comprising rotatable, radially reciprocable gripper mechanism mounted on said beam for engaging a moving signature and diverting a portion thereof at one side of the center thereof away from said path to thereby open the signature.

30 30. Apparatus as defined in claim 29 wherein said rotatable gripper mechanism includes suction gripper means.

31. Apparatus as defined in claim 29 comprising drive means mounted on the frame and operably connected with said gripper mechanism for rotating the same.

35 32. Apparatus as defined in claim 31 comprising means for adjusting said beam vertically relative to said drive means and said conveying means.

33. Apparatus as defined in claim 29 comprising a plurality of said last-named means on each side of said path, and means 40 for selectively rendering each of said plurality of means operable for diverting a portion of a passing suspended signature to open the same.

34. Apparatus as defined in claim 29 wherein said last-named means comprises a plurality of suction grippers mounted on each side of said path in spaced relation to each other, the grippers on each side being successively operable to engage an advancing signature.

35. Apparatus as defined in claim 34 comprising programming means driven in synchronism with the signature 45 conveying means for selectively controlling the operation of each of said suction grippers.

36. Apparatus for opening folded signatures comprising a stationary frame, a supporting beam mounted on said frame, means mounted on said frame for conveying a suspended signature edgewise in a path above and along said beam, and means mounted on said beam for engaging a moving signature and diverting a portion thereof at one side of the center thereof away from said path to thereby open the signature, said last-named means comprising a member extending across said path at an acute angle thereto for engagement by the lowermost marginal portion of a depending part of an advancing lapped signature.

37. Apparatus as defined in claim 36 wherein said member is inclined upwardly away from said path at one side thereof.

38. Apparatus as defined in claim 36 comprising means mounted on said beam for selectively moving said member into and out of operative position across said path.

39. Apparatus for feeding signatures one at a time in spaced 70 relation to a book-sewing machine or the like from a stack of folded signatures of varying composition flat gathered in a stack in predetermined book-forming sequence, said apparatus comprising a continuously operating, endless conveyor including a series of equally spaced signature grippers and having a lower horizontal reach from which the grippers

depend, rotary means for withdrawing signatures one at a time from said stack, roll feed means for receiving said signatures from said rotary means and delivering the same upwardly into said grippers traveling with said horizontal reach of the conveyor, said grippers engaging an edge portion of the signatures while supporting and transporting the same edgewise in suspension, means for opening each signature to its center while the same is advanced by said conveyor, and means for continuously driving said conveyor, rotary means, roll feed means and said signature opening means in predetermined timed relation.

40. Apparatus as defined in claim 39 comprising programming means for selectively controlling said signature opening means in accordance with the composition and sequence of the signatures being fed from said stack, said programming means being driven by said driving means in timed relation with the feeding of the signatures.

41. Apparatus as defined in claim 39 comprising means for rotating said depending grippers relative to the conveyor together with the opened signatures suspended therefrom.

42. Apparatus as defined in claim 39 comprising a saddle

conveyor, and means for actuating said grippers to release opened signatures to drop onto said saddle conveyor.

43. Apparatus as defined in claim 42 comprising means disposed intermediate the ends of said saddle conveyor for compressing the backbone folds of the signatures, said compressing means including intermeshing rollers engaging the inner and outer surfaces of said folds.

44. Apparatus as defined in claim 43 comprising resilient means for urging said rollers into compressing relation with said folds.

45. Apparatus as defined in claim 39 wherein said signature-opening means comprises at least one suction gripper for initiating the opening of a signature and a guide rod for completing such opening in response to movement of the signature by said conveyor.

46. Apparatus as defined in claim 39 wherein said signature-opening means comprises at least one member extending across the path of the advancing signatures for engagement by the depending lap portion of a lapped signature.
